HENRY M. JANVILLE, OF MAYBROOK, NEW YORK

PROTECTIVE SWITCH MEMBER

Application filed October 14, 1929. Serial No. 399,438.

The main object of this invention is to provide an apron which is mounted between the movable members of a switch and spans the entire distance between the tracks and is 5 raised above the switch operating mechanism serving as a protective member to prevent any loose or hanging parts of a train from coming in contact with the switch operating mechanism and disabling the same.

10 The above and other objects will become apparent in the description below in which characters of reference refer to like-named parts in the drawing.

Referring briefly to the drawing, Figure 1 15 is a perspective view of the switch apron as applied to its proper position between parallel rails at a switch location.

Figure 2 is a longitudinal, sectional, side elevation view of Figure 1.

20 Referring in detail to the drawing, the numeral 10 indicates one of the rails of a track system. This rail is curved at the switching position and branches to another parallel track system adjacent. The numeral 11 indicates a substantially straight linear rail which forms the companion member of rail 10. These rail members, 10 and 11, are mounted on a plurality of side by side arranged ties 12 which are conventionally set upon a bed 30 of ballast stone. The rail 10, which branches to an adjacent pair of rails, is rigidly mounted upon the ties and the rail 11 is also mounted on these ties in the same condition, that is, rigidly. In switching or shifting railway 35 carriers from one pair of tracks, such as indicated by the numerals 10 and 11, to an adjacent pair of tracks, movable switching rails are used. One of these movable switch rails is indicated by the numeral 13. Said switch rail is connected to a rigid branch rail 14 by straps 15 in the conventional manner and is capable of lateral movement. The tip 16 of the movable switch rail 13 tapers gradually to a point and is adapted, when the 40 switch is set, for shifting, to lie adjacent the side face of the rail 11. This position is not shown in Figure 1.

The opposing switch rail is indicated by the 45 numeral 17 and is shown in a position lying adjacent the curved stationary rail 10. These

switch rails 13 and 17 which shift carriers from one set of rails to an adjacent set are actuated by a switch lever not shown on the drawing. The switch mechanism comprises a strap 18 which is connected by brackets 55 19 to a connecting rod 20. This connecting rod joins the switch rails 13 and 17 at the free ends thereof and, being very delicate, is readily injured or deformed causing open switches.

60 The invention consists in providing an apron which rises to the level of the carrying surface of the rails 10, 11, 13 and 17. The apron comprises a horizontal plate 21 which covers the switch rail operating mechanism and is supported upon high beams 22 and 23. This plate is recessed at 24 and 25 on opposing sides thereof in order to permit the passage of the tips of the switch rails 13 and 17 into these recesses alternately according to 65 the direction in which the carriers are to pass. The protective plate 21 is provided with inclined aprons 26 on opposite sides thereof which have extensions 27 thereon secured in place upon a convenient tie by bolts 28. Ledges 29 are provided at the extremities of the aprons which form shoulders for locating the protective member supporting ties 30.

70 It has been established by railway engineers that wrecks and derailments occur through reason of faulty switch units. The switch rail operating mechanism is generally rendered faulty by passage of the proceeding carrier or train. It frequently occurs, especially on freight trains, that parts of the suspended mechanism, such as brake beams or the like, will drag at one end and, in passing over the switch crossing, come in contact with the switch operating mechanism with the consequence that the switch operating mechanism is either badly deformed or fractured. The train crew or switch operator who reverses the switch for shifting when using the switch upon an ensuing occasion 75 will not notice this deformed switch and will shift the rails 13 and 17, one of which, with the connecting rod 20 deformed, will not come in contact with its cooperating stationary rail, either 11 or 10. When this occurs, one 80

switch rail will not perform its function with a consequent derailment of the carrier passing through the switch. To prevent this dangerous and property destroying derailment, I provide a raised member 21 from which inclined aprons 26 extend and are mounted upon the ties on both sides of the switch rails. These members completely guard, conceal, cover and protect the switch 5 operating mechanism and, should any dragging devices on the carrier exist which is being drawn over the switch, they will be lifted by the protective member over the mechanism concealed thereunder and will, therefore, be 10 prevented from injuring this mechanism. 15

It is to be noted that certain changes in form and construction may be made without departing from the spirit and scope of the invention.

20 I claim:

1. A device of the class described comprising in combination a straight linear rail, an adjacent angular movable switch rail, a companion curved stationary rail, and a companion switching rail mechanism for switching said switching rail, ties supporting said rails, inclined aprons mounted on said ties and a horizontal plate unitary with said apron joining the same and raised above the 25 switch rail operating mechanism for protecting the same, recesses in said plate for receiving the switch rail end therein when said switch rail is in opened position.

2. A device of the class described comprising in combination a straight linear rail, an adjacent angular movable switch rail, a companion curved stationary rail, and a companion switching rail mechanism for switching said switching rail, ties supporting said rails, 30 inclined aprons mounted on said ties and a horizontal plate unitary with said apron joining the same and raised above the switch rail operating mechanism for protecting the same, a recess on each side of said plate, either 35 of said recesses being adapted to alternately receive one or the other of said switch rails when said switch rail mechanism is operated.

3. A device of the class described comprising in combination a straight linear rail, an 40 adjacently positioned angular movable switch rail, a companion curved stationary rail and a companion switching rail, ties supporting said rails, inclined aprons mounted on said ties and a horizontal plate unitary with said 45 apron joining said aprons at their upper ends, said plate being raised above the switch rail operating mechanism for protecting the same, a recess on each side of said plate extending in the same general direction as the rails, said 50 recesses being adapted to alternately receive one or the other of said switch rails when said switch rail mechanism is operated.

In testimony whereof I affix my signature.
HENRY M. JANVILLE.
